UNITED STATES PATENT OFFICE.

JAMES P. GORMAN, OF NEW YORK, N. Y.

COLLAR.

1,218,254.

Specification of Letters Patent.

Pat. Mar. 6, 1917.

Application filed September 17, 1914. Serial No. 862,134.

To all whom it may concern:

Be it known that I, JAMES PAUL GORMAN, a citizen of the United States, and resident of the borough of Manhattan, city, county, and State of New York, have invented certain new and useful Improvements in Collars, of which the following is a specification.

The adoption of the soft fold collar has introduced a problem to the collar makers, one that is rather difficult to overcome in a convenient and yet simple manner.

It is found that these very peculiar collars break and fall down and that they do not hang close to the neck or in an upright position. I have provided a means for supporting a collar of this style, a means secured to the collar and one that is simple in operation and yet highly efficient, and a series of experiments have demonstrated to me that the principle of my improvement is correct and that it can be depended upon to perform its functions in a satisfactory manner. The construction and operation of my device will be fully set forth as the specification progresses.

The following is what I consider the best means of carrying out this invention and the accompanying drawings form a part of this specification in which:

Figure 1, is a plan view of a collar unfolded.

Fig. 2, is a plan view of the collar folded, the fracture disclosing one of the tabs folded in place. In this view the collar is in an upside down position.

Similar reference numerals indicate like parts in all of the figures where they appear.

At 1 I have shown the band of a collar and at 2 the folded portion of the collar. Although these parts may be formed in any well known manner the style I have here shown is an ordinary design of collar and one that will prove attractive and satisfactory to the wearer. The band and folded portion are secured together in the well-known manner of stitching and it is advisable that the collar and band be of sufficient thickness or of sufficient layers or ply as it is called, to provide a body that will take and retain the proper finish.

It is my intention that the band and fold of the collar should be soft laundried, although it will be fully understood that these

parts may be stiffened to any desirable extent.

Secured to the band 1, and projecting therefrom, I arrange a plurality of tabs 3, 4, 5. These tabs should also be formed from a number of thicknesses of cloth and I prefer that they should be of a length equal to the width of the band 1. These tabs are secured to the band at the edge directly opposite that to which the fold is secured and it will be observed that they may be stitched into the band when the band is formed.

I also provide the ordinary button holes 6, 7 and 8 in the band 1, by means of which the collar is secured to the neck band of a shirt.

I have before set forth that the band 1, and the fold 2 should be soft laundried that is, laundried without starch, but I intend and prefer that the tabs 3, 4 and 5 should be starched to a great degree so that they will be stiff and to a great extent rigid. The tabs 3, 4 and 5 should be folded upon the band 1 and the fold 2 should then be arranged for the tabs as indicated in Fig. 2.

The tabs 3, 4 and 5 in my construction perform a double function. With the collar as prepared as set forth and the wearer desires to place the collar in service, the fold 2 is lifted and the tabs 3, 4 and 5 are turned outward, the band of a scarf or cravat is placed about the band 1, of the collar, the tabs 3 and 5 are folded inward upon the scarf and the fold 2 is then arranged over the tabs 3, 4, and 5. It will be seen then that the tabs will not only retain the scarf in position but will also support the band and fold of the collar and the center tab may be caused to cover the button to prevent it from interfering with the free movement of the tie. The third function of these tabs and one of great importance is their ability to provide a passage for the easy movement of the scarf. As the tabs are stiffened they cannot be forced into a close engagement with the band 1, but the roundness of the fold as indicated at 9 insures that they remain a sufficient distance away from the scarf to provide an easy movement thereof.

Modifications may be made within the scope of the appended claim without departing from the principle or sacrificing the advantages of this invention.

Although I have described my improve-

ment as forming a part of a soft fold collar I desire it understood that many of the advantages will be gained from its use with a stiff collar or as a part thereof. I further desire it understood that I do not insist upon the construction of a collar of this particular design as any of the well known types will serve as well.

Having carefully and fully described my invention what I claim and desire to secure by Letters Patent is:—

A collar comprising a main inner securing flap, an outer turn down flap providing a tie space, means connected to the lower edge of the securing flap and foldable up-

wardly between the main and turn down flaps for the purpose of holding the tie from slipping downwardly, and a tap secured to the lower edge of the securing flap at the center and foldable rearwardly and upwardly between the tie and the securing flap to protect the tie from the collar button. 20

Signed at New York city, in the county of New York and State of New York this 8 day of Sept. 1914.

JAS. P. GORMAN.

ARTHUR PHELPS MARR,
THOMAS WATSON.

It is hereby certified that in Letters Patent No. 1,218,254, granted March 6, 1918, upon the application of James P. Gorman, of New York, N. Y., for an improvement in "Collars," an error appears in the printed specification requiring correction as follows: Page 2, line 18, claim, for the word "tap" read *tab*; and that the said Letters Patent should be read with this correction therein that the same may conform to the record of the case in the Patent Office.

Signed and sealed this 18th day of June, A. D., 1918.

[SEAL.]

F. W. H. CLAY,

Acting Commissioner of Patents.
